Inventor

United States Patent Office.

HENRY FARMER, OF PONTIAC, MICHIGAN.

Letters Patent No. 73,086, dated January 7, 1868.

IMPROVEMENT IN POTATO-PLANTERS.

The Schedule referred to in these Letters Patent and making part of the same.

Be it known that I, HENRY FARMER, of Pontiac, Oakland county, Michigan, have invented a new and improved Mode of Constructing Potato-Planters; and I do hereby declare that the following is a full and exact description thereof, reference being had to the accompanying drawings, and to the letters of reference marked thereon.

The nature of my invention consists of a band moving on rollers, which band has attached to it iron or other metallic fingers, which, taking the potatoes from a hopper, drop them behind the plough.

To enable others skilled in the art to make and use my invention, I will proceed to describe its construction and operation by a particular reference to the accompanying drawings, in which—

Figure 1 gives a general exterior view of the complete planter.

A is the hopper, B is the driver's seat, and M the pole, to which the horses are hitched. E is a wheel, which is moved by the axle of the large wheel F. R is a roller, shown in Figure 2, which presents a section of the machine. n n n n, in fig. 2, is a belt or band, which passes around the wheel E and the roller R. The wheel E has cogs, so as to set in motion the band or belt n n n n. Attached to the belt or band n n n n is a series of iron or metallic fingers, of the form shown in Figure 3. At the point P there is a grate, through the bars of which the iron fingers pass when the band or belt n n n n is in motion. This grate, and the mode in which the fingers pass between the bars, are shown in Figure 4. D is a spout, which delivers the potatoes in the furrow just behind the plough, marked G. H H are scrapers, which cover up the potato after it is dropped into the furrow.

The action of the machine is substantially as follows: The potatoes are put in the hopper A, and fall upon the grate P, where they are seized by the fingers on the belt passing through the bars of the grate; they are then carried over the roller R, and delivered into the spout D, from whence they fall into the furrow made by the plough G, and are then covered up by the scrapers H H.

The wheel E may be thrown out of gear by the lever I, in the ordinary mode. L is an attachment, by which the height of the ploughs may be regulated by the use of the lever I and rod K, shown in fig. 1. The fingers may be placed at longer or shorter intervals apart on the belt n n n n, as desired, to regulate the spaces at which the potatoes are to be dropped, the belt n n n n being pierced with holes at various spaces for that purpose, the iron or metallic fingers being movable. The fingers are affixed to the belt by a screw and nut, and are so arranged that they may be made to project a greater or lesser degree, as desired, so as to accommodate themselves to seize larger or smaller potatoes.

The construction of the machine may be varied by leaving out the belt n n n n and roller R, and by placing the fingers, in the mode above described, around the circumference of a single wheel of the proper size, to be set in motion in the same way as the wheel E. One of the large wheels of the "planter" is fixed to the axle, so as to move the wheel E, and the other large exterior wheel, marked S, in fig. 1, is left free on the axle, so as to permit turning the machine around. The space also between the two large exterior wheels F and S, fig. 1, may be increased or diminished, by moving them on the axle, which has holes and pins for that purpose. This is for the object of regulating the distance between the rows of the potatoes when planted.

What I claim as my invention, and desire to secure by Letters Patent, is—

The arrangement and combination of the said iron fingers, hopper, and ploughs, acting together as and for the purpose above specified.

HENRY FARMER.
